UNITED STATES PATENT OFFICE.

CLAUDE C. GOULD, OF BUFFALO, NEW YORK, ASSIGNOR TO THE EASTERN TELEPHONE SWITCHBOARD COMPANY, OF CAMDEN, NEW JERSEY.

ANNUNCIATOR.

SPECIFICATION forming part of Letters Patent No. 564,746, dated July 28, 1896.

Application filed September 28, 1891. Renewed December 12, 1895. Serial No. 571,958. (No model.)

To all whom it may concern:

Be it known that I, CLAUDE C. GOULD, a citizen of the United States, residing at the city of Buffalo, in the county of Erie and State of New York, have invented a new and useful Improvement in Annunciators, of which the following is a specification.

This invention relates to an annunciator which is more especially desirable for the switchboards of telephone-exchanges, but which is equally useful for the call-service of hotels and the various other uses of electric annunciators.

The objects of my invention are to produce an annunciator which is simple in construction and cheaply manufactured, and to so organize the annunciator that the same movement whereby its visual signal is replaced connects a talking or signaling circuit with the main line, thus reducing the number of movements and the time incidental to connecting the subscribers of a telephone-exchange or establishing communication between the rooms of a hotel or other building.

In the accompanying drawings, consisting of two sheets, Figure 1 is a side elevation of my improved annunciator secured to a switchboard or other support and showing the parts in a normal position. Fig. 2 is an elevation of the opposite side thereof. Figs. 3 and 4 are opposite side elevations corresponding to those of Figs. 1 and 2, showing the position of the parts when the signal is projected and the local bell or signaling-circuit is connected with the main-line circuit. Fig. 5 is a top plan view of the annunciator. Fig. 6 is a longitudinal section thereof, partly in elevation. Fig. 7 is a rear view of the same. Fig. 8 is a cross-section in line xx , Fig. 6, looking toward the left. Fig. 9 is a similar section in line xx , Fig. 6, looking toward the right. Fig. 10 is a side elevation of the annunciator, showing the position of the parts when the talking-circuit is connected with the main-line circuit and also showing a pedal-switch for calling or signaling a subscriber.

Like letters of reference refer to like parts in the several figures.

For convenience my improved annunciator will be described in connection with a telephone system.

A is the switchboard or other support, and B the frame of the annunciator, consisting, preferably, of a tube secured with its front portion in an opening in the switchboard by screw-nuts applied to the threaded end of the tube and bearing against opposite sides of the board, as shown.

C is the coil of the annunciator supported by a suitable frame secured to the tube B, and c is its armature, which is pivoted to the frame of the coil.

D is a plunger or follower arranged to slide in the tube B and carrying a push-button E, arranged at the front end of the tube and connected with the plunger by a stem e. The push-button E also serves as a visual signal, and for this purpose its face bears a numeral or other character designating the line of the person or subscriber which it represents. The stem of the push-button is guided in a perforated block or diaphragm e', arranged in the front portion of the tube B.

F is a spiral spring arranged in the tube behind the plunger D and which tends to force the plunger forward, so as to project the button or signal E. As shown in Figs. 6 and 7, the front end of the spring F bears against the rear side of the plunger and its rear end abuts against a pin f, passing transversely through the rear end of the tube B.

G is a catch or locking-bolt controlled by the armature of the annunciator-coil and whereby the plunger is retained in its inner normal position against the pressure of the spring F. This catch is suspended from a rearwardly-extending arm g, arranged on the pivoted armature c, and its lower end passes through an opening in the upper side of the tube B and interlocks with its abrupt rear face with a shoulder d, formed on the adjacent side of the plunger. The lower end of the catch is beveled or inclined on its front side, as shown in Fig. 6, so that the catch is raised when struck by the rear end of the plunger during the inward movement of the same, the catch

descending and engaging with its abrupt side against the shoulder of the plunger as soon as the enlarged rear portion of the latter has passed beyond the catch. The catch is prevented from entering the tube B too far by a shoulder g' , formed by reducing the end portion of the catch. When the annunciator-coil is excited, the catch is lifted out of engagement with the plunger by the movement of the armature, thereby permitting the compressed spring F to force the plunger outward and projecting the push-button or visual signal.

H is a cross-bar of insulating material supported upon a metallic standard H', secured to the upper side of the tube or frame B and projecting laterally beyond the sides of the tube.

d' is a contact pin or projection secured to one side of the plunger and extending through a longitudinal slot b , formed in the tube B.

i is the incoming line-wire, and i' a wire leading from the latter to one end of the annunciator-coil.

h is a depending contact-spring secured to the end of the cross-bar H on the same side of the tube B as the conducting-pin d' , and h' is a wire leading from said contact-spring to the adjacent end of the annunciator-coil. The spring h is arranged with its flat side at right angles to the contact-pin d' , so that the latter rests against the flat inner face of the spring, in the position of these parts represented in Figs. 2, 7, and 8.

j is a wire connecting the metallic standard H' with the ground. Electrical connection is established between the standard H' and the contact-pin d' through the plunger D and the metallic tube B. In the normal position of the parts shown in Figs. 1, 2, 5, 6, 7, and 8 a current over the main line i passes through the branch wire i' , coil C, wire h' , contact-spring h , contact-pin d' , plunger D, tube or frame B, standard H', and wire j to the ground, thus exciting the coil, releasing the catch F from the plunger, and projecting the visual signal D.

k is a contact-spring secured at its upper end to the cross-bar H on the same side of the tube B as the contact-pin d' , and arranged in the path of the latter in front of the spring h , so that the pin comes in contact with the lower end of said spring k when the plunger is in its outward position, as represented in Fig. 4.

K is a local bell or signal for the operator located at the telephone-exchange, and k' is a wire leading from said bell to the contact-spring k . When the button or visual signal E is projected, the current passes from the ground wire j through the standard H', tube B, plunger D, contact-pin d' , contact-spring k , wire k' , and local bell K to the ground, thus ringing the local bell and signaling the operator, who observes from the projected visual signal which subscriber has called.

Referring to Figs. 1, 3, 8, and 10, l is a de-

pending contact-spring secured to the end of the cross-bar H on the side of the tube H opposite from the contact-springs h and k , and l' is a branch wire connecting said contact-spring with the main-line wire i .

m is a depending contact-spring secured to the cross-bar H adjacent to the rear side of the contact-spring l . The spring m is adapted to be connected with the spring l by deflecting the latter rearwardly, as shown in Fig. 10.

n is an insulated pin or projection carried by the plunger, on the side thereof, diametrically opposite the contact-pin d' , and which passes through a longitudinal slot n' , formed in the tube B. The pin n is insulated by a sleeve or covering of non-conducting material, as shown. The front contact-spring l is arranged in the path of the insulated projection n , and its position is such that it is deflected rearwardly against the rear contact-spring m by the final portion of the inward movement of the plunger and push-button, but not when the push-button and plunger are in the normal position. (Shown in Figs. 80, 1, 2, 3, and 4.)

For this purpose the shoulder of the plunger, with which the catch F interlocks, is so located as to leave the button at a short distance from the front end of the tube B, when in its normal position, so as to afford the button sufficient further inward movement to press the contact-spring l against the rear spring m . The latter is preferably formed at its lower end with a forwardly-bent lip m , against which the front spring l bears.

o is a wire leading from the rear contact-spring m to the operator's telephone or talking mechanism, which latter may be of any ordinary or approved construction.

While any suitable talking device may be connected with the annunciator, I prefer to employ the combined talking and calling or signaling mechanism forming part of Fig. 10. This mechanism consists, essentially, of a rectangular frame P, an upper contact-spring p , which is connected with the telephone Q by a wire q , a lower contact r , connected with a battery R by a wire r' , and a vertically-sliding pedal-switch or push-rod S, carrying a contact-pin or projection s , adapted to engage alternately with the upper and lower contact-springs p and r .

t are dead-springs arranged opposite the contact-springs p and r and which merely form supports for the adjacent portion of the contact-pin s , so as to properly guide the pin and prevent binding thereof.

u is a contact-spring bearing at all times against the lower portion of the sliding push-rod S and with which the wire o is connected. The push-rod is guided in the frame P in any suitable manner and is held in an elevated position by a spiral spring S', surrounding the same. When the pedal-rod is in its elevated position and the push-button is pressed to its extreme inner position, as shown

in Fig. 10, the operator's telephone is connected with the main line through the wire *q*, upper contact *p*, contact-pin *s*, pedal-rod *S*, contact *u*, wire *o*, rear and front contact-springs *m* and *l* of the annunciator, and the wire *l'*. Upon pressing the push-button *E* to its extreme inner position and depressing the pedal-rod *S* the operator's telephone is cut out of the circuit and the battery is switched in through the wire *r'*, contact *r*, contact-pin *s*, pedal-rod *S*, contact *u*, wire *o*, the rear and front contact-springs *m* and *l* of the annunciator, and the wire *l'*.

Upon pushing the visual signal or button *E* to its innermost position for switching in the talking or signaling circuit, the contact *d'* passes beyond the stationary spring *h*, out of contact therewith, thereby throwing off the ground connection through said spring and shunting the current through the operator's talking or signaling circuit.

The operation of my improved annunciator is as follows: When a subscriber calls the telephone-exchange, the visual signal of the corresponding annunciator is projected, and as soon as the plunger *D* reaches its outermost position the operator's call-bell is switched into the circuit and sounded, thus notifying the operator of the call. The operator now pushes the button or visual signal clear into the tube, as shown in Fig. 10, whereby his telephone is connected with the circuit and his call-bell cut out. Upon finishing the conversation, the operator switches in the battery to ring off by depressing the pedal-rod *S*. After ringing off, the operator releases the push-button *E* and the pedal-rod, whereby the push-button returns to its normal position and the operator's telephone is again placed in communication with the front contact-spring *h* of the annunciator, ready for another call. It will thus be noticed that the push-button takes the place of the aprons or drops heretofore employed and that the operator's telephone is connected with the main line in the act of replacing the projected button or visual signal, thus requiring fewer movements to connect subscribers than with the annunciators heretofore in use, simplifying the work of the operator and enabling him to make connections with greater despatch.

My improved annunciator is described and shown as applied to a closed battery-circuit; but it may obviously be employed in connection with a magneto-circuit.

If desired, any other suitable talking and ringing circuits than those shown and described may be connected with the contacts *m* and *l* of the annunciator.

I claim as my invention—

1. In an annunciator, the combination with a horizontal tube forming the frame of the annunciator, of a plunger or follower sliding in said tube and carrying a contact, an electric magnet and its armature supported on said

tube, a catch adapted to engage with said plunger and controlled by said armature, a spring whereby said plunger is projected when released, and a contact-terminal included in a circuit and arranged to connect with the contact of the plunger, substantially as set forth. 70

2. In an annunciator, the combination with a horizontal tube forming the frame of the annunciator, of a plunger or follower sliding in said tube and carrying a contact, a signal-button connected with said plunger and arranged to project beyond the front end of said tube when the plunger is moved outward, substantially as set forth. 75

3. In an annunciator, the combination with a supporting-tube and an electromagnet and its armature supported thereon, of a plunger or follower sliding in said tube and carrying a contact, a catch engaging with said plunger and controlled by said armature, a spring for projecting the plunger when released, and terminal contacts arranged in the path of the plunger-contact in front and in rear thereof, whereby the plunger-contact bears against said rear terminal in the inner position of the plunger and against said front terminal in the outer position thereof, substantially as set forth. 90

4. The combination with the tubular base or frame of the annunciator, of a coil or magnet and its armature, a plunger or follower arranged in the tubular base and carrying a contact, a push-button or visual signal connected with the plunger, a catch whereby the push-button is locked in its normal position, a spring whereby the push-button is projected when released from its catch, and a contact or terminal arranged adjacent to the catch of the plunger and with which the plunger-contact is adapted to engage, substantially as set forth. 95

5. The combination with the base or frame of the annunciator, of a coil or magnet and its armature, a plunger or follower sliding on said base or frame, and provided on one side with a projection and on its opposite side with a contact, a push-button or visual signal connected with said plunger, contacts arranged on the base or frame in front and in rear of the plunger-contact and adapted to engage alternately with the same, and a contact arranged on the base in the path of the projection of the plunger, substantially as set forth. 110

6. The combination with the base or frame of the annunciator, and an electromagnet and its armature, of a plunger or follower guided in said base or frame and provided on one side with a contact and on its opposite side with a projection, a catch engaging with the plunger and controlled by said armature, a spring whereby the plunger is moved outward when released, a contact or terminal arranged to bear against the plunger-contact in the normal position of the latter, a termi- 125

nal included in a signal-circuit and arranged to connect with the plunger-contact, in the projected position of the latter, a contact-spring included in a talking-circuit and arranged to be deflected by the projection of the plunger when the latter is pressed inward beyond its normal position, and a contact-terminal also included in said talking-circuit

and arranged adjacent to said contact-spring, substantially as set forth. 10

Witness my hand this 2d day of September, 1891.
